UNITED STATES PATENT OFFICE.

WILBUR S. SCUDDER, OF BROOKLYN, NEW YORK, ASSIGNOR TO THE MONOLINE COMPOSING COMPANY, OF WASHINGTON, DISTRICT OF COLUMBIA, A CORPORATION OF WEST VIRGINIA.

LINE-CASTING MACHINE.

SPECIFICATION forming part of Letters Patent No. 733,559, dated July 14, 1903.

Application filed October 16, 1901. Renewed November 5, 1902. Serial No. 130,149. (No model.)

To all whom it may concern:

Be it known that I, WILBUR STEPHEN SCUDDER, a citizen of the United States, and a resident of Brooklyn borough, New York, State of

5 New York, temporarily residing at Montreal, in the county of Hochelaga and Province of Quebec, Canada, have invented certain new and useful Improvements in Line-Casting Machines; and I hereby declare that the following is a full, clear, and exact description of the same.

This invention relates to certain new and useful improvements in that class of line-casting machines known as the "monoline," 15 which is fully described in my Letters Patent of the United States No. 506,198, dated October 3, 1893, and No. 605,141, dated June 7, 1898, and to which reference is made.

My present invention relates to certain new 20 and useful improvements in the pot in which the type-metal is melted and in the mold for casting lines of predetermined length and thickness.

Metal-pot.—At present in line-casting machines the metal-pot is made of a solid casting on account of the variable shapes that it is necessary for it to assume to accommodate the predetermined space in the machine and also for reasons of economy in its manufacture. By reason of the heavy strain of the large store of metal carried therein and the numerous variations of temperature to which the metal-pot is daily subjected the cast-iron does check and from time to time form leaks 35 which seriously interfere with the successful operation of this part of the machine. This is more pronounced in the "lighting up." When a full flame is turned on the pot filled with type-metal, the metal nearest the flame 40 becomes heated, expands, and forces the cast-iron of the pot to expand before the type-metal at the top of the pot becomes fluid. To overcome the difficulty occasioned by this unequal expansion and contraction, I have constructed the metal-pot of one piece of sheet-steel pressed into the desired shape, the sides and ends of the pot being provided with vertical corrugations extending from the bottom to the top, which by expanding laterally relieve the sides and ends of the pot of the

strain carried by the longitudinal and unequal expansion that takes place as the metal is being heated, thus preventing the checking and subsequent leaking of the pot.

Mold.—In line-casting machines using a laterally-moving mold but one aperture has heretofore been provided, it being the custom when other measures were required to take out the mold-box and insert another one containing the desired measure. This invention provides a mold-box which will have a plurality of apertures for casting lines of predetermined length and thickness and a frame in which the mold-box is carried movable at right angles with the fixed travel of the mold, thus allowing the mold-box to be adjusted from one position to another to bring into play the predetermined aperture.

For a full understanding of my invention reference is had to the accompanying drawings, forming a part of this specification, in which like symbols indicate the same parts, and wherein—

Figure 1 is a front view of the mold-slide of the monoline-machine to which my invention is applied. Fig. 2 is a sectional view on the line *a b* in Fig. 1. Fig. 3 is a plan view of the several parts, and Fig. 4 is a sectional view on the line *c d* of Fig. 3. Fig. 5 is a perspective view of the cam-ring for adjusting the position of the supporting-block. Fig. 6 is a view of the supporting-block, showing it and the cam-ring in the position shown in Fig. 1. Fig. 7 is a similar view to Fig. 6, showing the cam-ring and supporting-block in their alternative position.

Metal-pot.—The Letters Patent heretofore referred to show merely a cast-iron pot of an oblong shape within a protecting-jacket, which jacket acts both as a protector for the other parts of the machine to keep the heat confined and as a frame through which the pressure of the pot-cam is conveyed to the front of the machine and applied to the mouth of the metal-pot to properly lock it against the mold to prevent leakage of metal at the instant of casting the line. My new pot does not alter any of these conditions, but substitutes for the cast-iron pot a pressed-steel pot 1, the sides and ends of which are 100

provided with corrugations 2 and corner-folds 3. While I am fully aware that the pressing of sheet metals into desired shapes is well known to the trade, yet as applied for use in machines of this class it presents a marked advance over metal-pots made in the usual manner for line and type casting machines, and the corrugations by compensating for the unequal expansion of the sides and ends of the pot enable it to withstand the greatest degree of heat without damage and conduct the heat to the metal at much less expense for heating material than otherwise, the corrugations rendering the pot elastic enough to withstand the usual variations of temperatures incident to the heating and chilling of the type-metal.

Compound mold.—In the accompanying drawings the mold-slide is constructed in the usual manner, the top half or section 4 and the bottom section 5 being separated at their outer or free ends by the separating-block 6, the opposite ends of the sections being attached to the supporting-block 7, pivoted on the mold-slide stud 8. At the base of the mold-slide stud 8 is placed a cam-faced ring 9, supplied with a lever 10 to facilitate the adjustment of the cam-faced ring 9. In the separating-block 6 I have shown two slots 11, in the upper one of which is fitted a removable guide-piece 12, suitably attached to the upright knee 13. The completed slide, as shown, thus forms a frame which can be swung on the stud 8, its outer or free end being guided and supported by the guide-piece 12. By the temporary removal of the guide-piece 12 and the turning of the cam-faced ring 9 the entire slide can be shifted to another position as much higher as the thickest part of the cam-faced ring 9 will give. The guide-piece 12 can be then replaced in the corresponding slot 11 and the new position of the slide made secure. Traveling laterally in the opening formed by the two sections 4 and 5 of the mold-slide is the mold-box 14, motion to which is imparted through the link 15 and the lever 16. In the mold-box I have shown two apertures 17 and 18 for casting lines, the upper one, 17, of which is in position for casting. In Fig. 2 I have shown in dotted lines the mold 14 and the mold-slide shifted to the upper position, thus bringing the lower mold 18 into position for casting. Near the mold-slide stud 8 of the mold-slide I have attached to the lower section 5 of the mold-slide a bracket 19 on the front side of the same, which is suitably formed to carry the trimming-knives 20. Directly opposite and attached to the lower section of the mold-slide 5 is the bracket 21, which is provided with a dovetailed slide 22, upon which is mounted two ejector-blades 23. The rear end of the slide 22 has a tenon formed therein, 24, which is fitted loosely in the mortise formed in the ejector-slide 25. This ejector-slide 25 is similar to that in use

on the monoline and takes motion in the same manner through the ejector-fork 26 and the cam 27. In order to give motion at proper intervals to the free end of the mold-slide, the bracket 28 is attached thereto and is connected by a link 29 to the bracket 30, attached in turn to the pot-jacket 31. The pot-cam 32 is provided with steps to impart motion to the jacket 31 and through it to the connecting parts.

The operation of the mold-slide is similar to that described in the Letters Patent heretofore mentioned, the improvement consisting of means provided for shifting the entire mechanism to a new position, which brings into play any predetermined aperture in the mold-box 14 for casting the line and with it its own means for ejecting and trimming the line-bar so cast. It will be appreciated that the mold-slide may be enlarged and arranged to receive a larger mold-box 14, which would have a varied assortment of apertures for casting lines therein, than I have shown and be as easily and readily shifted to the different positions in the same manner as that above described. The connecting and moving mechanisms require no changing or positioning whatever, sufficient play being provided between the ejector-bracket 21 and the fixed part of the bed-plate carrying the slide 25 and in the connection 24 and between the bracket-slide 22 and the fixed slide 25 to permit the swing of the frame necessary in the operation of the machine. The knife-bracket 18 and the ejector-bracket 21 are rigidly affixed to the lower section 5 of the mold-slide and are, for mechanical purposes, a part of it. The ejector-blades 23, the mold-slots 17 and 18, and the trimming-knives 20 all bear toward each other fixed relations and are arranged to provide each aperture in the mold-box 14 with its own means for ejecting and trimming the bar cast.

Having thus fully described my invention, what I claim as new, and desire to secure by Letters Patent, is—

1. In a line-casting machine a type-metal pot having vertical corrugations extending from the top to the bottom of the sides and ends, to relieve the metal-pot of the strain of the unequal expansion and contraction of the metal, substantially as specified.

2. In a line-casting machine a type-metal pot having vertical corrugations extending from the top to the bottom of the sides and ends, and corner-folds at the junction of the sides and ends, to relieve the metal-pot of the strain of the unequal expansion and contraction of the metal-pot, substantially as specified.

3. In a line-casting machine a laterally-movable mold, having a plurality of apertures for casting lines of predetermined length and thickness in combination with a movable frame relatively adjustable to the laterally-movable mold, substantially as specified.

4. In a line-casting machine a laterally-movable mold, having a plurality of apertures for casting lines of predetermined length and thickness, in combination with a vertically-adjustable frame, a pivotal stud supporting one end of the frame, and a cam mounted on the stud to adjust the frame vertically, substantially as specified.
5. In a line-casting machine a laterally-movable mold, having a plurality of apertures for casting lines of predetermined length and thickness, in combination with a vertically-adjustable frame, a pivotal stud supporting one end of the frame, a cam mounted on the stud to adjust the frame vertically, and a stud

to rigidly support the other end of the frame when adjusted substantially as specified.

6. In a line-casting machine the combination of a laterally-movable mold, having a plurality of apertures for casting lines of predetermined length and thickness, in combination with a movable frame adjustable relatively to the mold, and means for ejecting and trimming the line-bars, substantially as specified. 20

Toronto, October 7, 1901.

W. S. SCUDDER.
